HYDRAULICALLY-ACTUATED APPARATUS FOR EXPRESSING LIQUIDS FROM FLOOR MOPS

William G. Van Voorhis and Albert J. Heider,
Columbus, Ohio

Application June 9, 1947, Serial No. 753,406

5 Claims. (Cl. 15—261)

1

The present invention relates to pressing devices for exerting pressure on various objects and substances through the employment of hydraulic means, and, more particularly, it deals with a device for exerting pressure on floor mops for the purpose of squeezing out of them soil-laden water with which such mops become filled while being used for cleaning purposes.

Mop presses or wringers, as heretofore constructed, have been objectionable in one or more of the following respects: they have required too much time in manual effort to operate them; they do not remove effectively and completely the dirty water with which floor mops become filled; there is a marked tendency to upset the tub or bucket on which such presses are usually mounted and, again, they are often insufficient in their pressing or wringing action, since their mechanical action is predicated on the use of mechanical advantages obtained through linkages, gearing, cams or rollers.

In order to overcome these and other objections or disadvantages present in mop presses of the prior art, it is an object of the present invention to provide a press which will require but a minimum of manual effort on the part of the operator thereof in obtaining efficient operation. In connection with the foregoing object, it will be realized that most of the users of such wringers are often elderly or infirm persons lacking in the physical strength required to operate the present clumsy and inefficient mechanical presses, and therefore it is an object of this invention to obtain a press in which positively applied high pressure forces may be set up with but small expenditure of physical energy.

Other objects of the invention are to provide a mop press which will operate with high efficiency, converting as many as possible of the foot pounds of energy applied to it into the performance of useful work; to provide a mop press which is relatively simple in construction and easy to maintain in service; to provide a mop press which will be operated by foot pressure in obtaining high compression rather than by hand pressure, thereby reducing fatigue as well as avoiding any tendencies to overturn or tilt the tub assembly when the press is actuated; and to provide an efficient press which is capable of being economically manufactured.

For a further understanding of the invention, reference is to be had to the following description and the accompanying drawings, wherein:

Fig. 1 is a side elevational view of a mop press

2

formed in accordance with the present invention;

Fig. 2 is a detail vertical sectional view disclosing the perforated mop-receiving press casing and its associated arcuately swinging compressor follower;

Fig. 3 is a vertical sectional view on the line 3—3 of Fig. 2;

Fig. 4 is a top plan view of the tub or receptacle 10 having the mop-receiving casing and its follower shown in their operative positions on the top thereof;

Fig. 5 is a detail perspective view of the compressor follower;

Fig. 6 is a detail vertical sectional view taken through the hydraulic mechanisms.

Fig. 7 is a similar view of the valve devices forming a part of the hydraulic system.

Referring more particularly to the drawings, the numeral 10 designates the base frame of our improved press, the frame being supported for movement across a floor surface by means of swiveled caster wheels, indicated at 11. Arranged on the base frame 10 is one or more water-holding receptacles or tubs 12, a single receptacle having been shown in the drawings, although it will be understood that any desired number of receptacles may be used; for example, the receptacle 12 may be used to receive dirt-laden water, while another receptacle may be used to receive clear rinsing water. If desired, a single receptacle may be used, as disclosed, having a vertical partition 13 therein dividing the interior of the receptacle into a soiled water-containing compartment 14 and a rinse water-receiving compartment 15.

The receptacle is formed with an open top, reinforced by a rolled flange 16. Secured to and positioned in the upper portion of the compartment 14 of the receptacle is a mop-receiving casing 17, which includes an arcuate bottom wall 18, spaced vertically positioned side walls 19 and a vertical back wall 20. These walls are perforated as at 21 for the passage of fluids therethrough. The side walls 19 are riveted, bolted or otherwise secured to the walls of the receptacle 12, as indicated at 22.

The side walls 19 have their upper edges toward the rear thereof formed with bearings 23 which receive a horizontally disposed rock shaft 24. The rock shaft has secured thereto intermediate of its ends, the inner end of a manually operated handle 25. Also, the rock shaft is of such length that one end thereof projects beyond one of the bearings 23, as shown in Figs. 3 and 4,

and to this projecting end of the rock shaft there is fastened a crank arm 29, which is adapted to be actuated by hydraulic means hereinafter described.

Between the bearings 28, the rock shaft has secured thereto a mop compressor 27. This compressor preferably comprises a metallic casting formed to embody an arcuate wall 28 which is disposed in substantially concentric relation to the arcuate bottom wall 13 of the casing 17. Formed with the wall 28 is a web 29, the latter having formed centrally therein a recess 30 for the reception of the lower end of the handle 31 of a janitor's floor mop when the yarn body 33 of the mop is positioned in the press chamber 34, as shown in Fig. 2.

The compressor includes side walls 35 which at their upper rear corners include bearings 36 for the rock shaft 24. Pins or the like 37 may be employed in securing the compressor to the rock shaft for unitary movement. One of the bearings 36 is also formed with a sleeve 38 in which the inner end of the actuating handle 25 is positioned and secured.

It will be evident that when the yarn body of a mop is positioned in the press chamber 34, as shown in Fig. 1, and the rock shaft partially rotated in the direction indicated by the arrow A, the web 29 applies pressure to the end of the yarn body of the mop by reducing the effective volume of the press chamber. This action crowds the yarn body of the mop toward the back wall 20 of the casing, compressing said body and forcing soil-laden water therefrom, which passes through the perforations 21 into the compartment 14 of the tub or receptacle 12. It will be observed that the press casing is arranged at one side of the receptacle so that the rinsing compartment 15 will be available without obstruction.

To enable greater pressures to be applied to the yarn body of a mop inserted in the press over those capable of being applied thereto by the operation of the arm and hand control afforded through the use of the handle 25, the present invention provides a hydraulic system, operated by foot pressure, to secure a highly efficient pressing action. This hydraulic system includes an oil or liquid reservoir 39, suitably mounted on a side of the receptacle 12 in a relatively elevated position. Fluid gravitates from the reservoir 39 through a pipe line 40, which extends to a cut-over valve casing 41. This casing includes a longitudinally extending bore 42 in which is slidably mounted a cylindrical valve member 43, the bore 42 communicating with a bore 44 disposed at right angles to the bore 42. Under normal conditions, gravity flow of fluid from the reservoir 39 moves the valve member 43 to a position providing for the flow of oil or the like from the bore 42 into the bore 44. A pipe member 45 connects the bore 44 with a check valve mechanism 46.

Mounted on the side of the receptacle 12 toward the bottom thereof is a pump comprising a cylinder 47 in which is slidably mounted a plunger or piston 48. One end of the cylinder 47 is joined by means of a pipe 49 with the bore 43 of the valve casing 41. The plunger or piston includes a rod 50 which extends exteriorly of the cylinder 47, and at its outer end has a pivotal connection 51 with the upper end of a short crank arm 52 formed with a foot-actuated pedal 53. This pedal is pivotally mounted as at 54 in connection with a receptacle 12. A coil spring 55 has

5 its lower end connected with the pedal and its upper end with the receptacle so that the normal tendency of the spring is to elevate the outer end of the pedal so that it will assume the position shown in Fig. 1.

10 It will be seen that the operator may, by applying foot pressure to the pedal, depress the latter against the resistance of the spring 55, thereby rocking the crank arm 52 to impart reciprocatory movement in a forward direction to the plunger or piston 48 of the pump. This results in displacing liquid from the pump and advancing the same through the pipe 49 to the valve casing 41. The pressure applied to the fluid by the pump slides the valve member 43 to a position obstructing gravity flow of fluid from the reservoir 39, thus enabling the fluid displaced by the pump to pass through the valve casing 41, exiting by way of the bore 42, and passing through the pipe 45 to the check valve mechanism 46.

15 Swiveled on the longer arm of the pedal 53 is a stud 56 having a transverse bore in which is slidably mounted a rod 57. The rod has fixed thereto a collar 58 which constitutes a seat for the upper end of a coil spring 59, the lower end of the spring being seated on the stud 56. The upper end of the rod 57 is pivotally secured as at 60 to a yoke provided on the lower end of a slideable rod 61, which is carried by the casing member of the check valve mechanism 46. The upper end of the rod 61 is adapted to engage the lower end of a valve stem 62, the upper end of this stem carrying a valve head 63 which is adapted to be brought into and out of engagement with a valve seat 64.

20 Leading from the top of the casing of the valve mechanism is a pipe 65 which conducts the operating fluid of the system to and from the lower end of a vertically positioned hydraulic ram 66. This ram includes a hollow cylinder 67 in which is slidably mounted a piston 68, the pipe 65 entering the lower end of the cylinder 67 below the piston 68. The latter includes a rod which extends through a packing in the top of the ram cylinder and is pivotally connected as at 69 with the lower end of a link 70, the upper end of said link being pivoted as at 71 to the crank arm 26 of the rock shaft 24.

25 Provided in the pipe 45 is a T-fitting 72 containing a check valve 73, and a pipe connection 74 leads from the fitting 72 to the pipe line 49. By this arrangement, the pump is primed with fluid upon the return stroke of its piston. The piston 68 in the ram cylinder 67 is normally pressed downwardly by a spring 75. Air-bleed valves may be provided in the pump cylinder 47 and in the pipe line connecting the check valve mechanism 46 with the ram cylinder, in order to release air when the system is being filled with fluid.

30 Operation

35 When the yarn body of a mop is inserted into the press casing, the handle 25 is actuated to swing the compressor head 27 in a downward direction, the head being thus brought into contact with the mop and may apply an initial water-extruding pressure thereto. During this operation, the piston in the ram 66 moves upwardly, and fluid readily passes under gravity flow from the reservoir 39, through the cut-over valve 41, the check valve 46 to the lower part of the ram cylinder. To apply final pressure to the mop, the operator steps on the pedal 53, forcing it downwardly against the resistance of the spring 55.

This actuates the pump piston, forcing fluid from the pump cylinder and through the cross-over valve 41, the valve member 43 moving to a position obstructing fluid flow to or from the reservoir 39. It will be noted that the valve member 43 prevents the passage of fluid straight through the bore 42 of the casing 41, either from the reservoir 39 or from the pump 47. In passing through the cross-over valve, the fluid is required to make a right angle turn.

When the pedal is depressed, the rods 57 and 61 move downwardly, thus allowing the valve head 63 to move freely in response to fluid pressures applied thereto. The pressure of the fluid expelled from the pump unseats the valve head and allows the fluid to pass by way of the pipe 65 to the lower part of the ram 66, producing pressure on the under side of the ram piston 68 and partially rotating the rock shaft 24 to force the movable press head 27 against the mop body to effectively and thoroughly remove therefrom soil-laden water. The foot pedal may then be released and the same allowed to return to its normal position under the action of the spring 55.

While the hydraulic mechanism has been shown as comprising a number of spaced cylinders or casings, it will be appreciated that these cylinders or casings may be embodied in one or more castings to simplify the construction and render the same more compact. Other variations or modifications will be apparent to those skilled in the art.

We claim:

1. In a press for expelling soil-laden water from the yarn body of a floor mop, a wheeled base, a liquid-receiving receptacle mounted on said base, a press arranged within and adjacent to the top of said receptacle for the reception of the yarn body of a floor mop, said press including a pivotally movable pressing head, a fluid pump supported externally of said receptacle, foot-actuated means for operating said pump, a hydraulic ram including a sliding plunger, means for transferring fluid under pressure from said pump to said ram, and motion transmitting means uniting said plunger with the movable head of said press for imparting pivotal movement thereto in response to the introduction of pressure fluid to said ram.

2. A press for wringing water from handle-carried mops comprising a receptacle; a press casing mounted in the top of said receptacle, said casing being formed with a perforate and arcuate bottom wall, spaced vertical side walls and an up-standing back wall defining an open top chamber for the reception of a mop; a shaft rotatably carried between said side walls; a pressing head carried by said shaft for swinging movement into and out of the chamber of said casing, said head being formed with a uniformly arcuate wall which upon movement of said head within said chamber is disposed in spaced concentric relation to the arcuate bottom wall of said casing and a slotted web projecting outwardly from the arcuate wall of said head for engagement with the handle-adjoining end of a mop upon swinging movement of said head into said chamber, the slotted web of said head when the latter occupies a position within said chamber being disposed in close-fitting relation to the side and bottom walls of said press casing; and means connected with said shaft for imparting swinging movement to said pressing head.

3. A press for wringing water from handle-carried mops comprising a receptacle; an open top

perforate casing carried in the top of said receptacle and formed with a uniformly arcuate bottom wall, said casing providing an open top chamber for the reception of a handle-carried mop; a shaft extending transversely of said casing and journaled therein for axial rotation; a pressing head secured to said shaft and movable upon rotation of the latter into and out of the chamber of said casing; said head comprising a uniformly arcuate and imperforate wall which upon movement of said head within the chamber of said casing occupies a position in spaced concentric relation to the arcuate bottom wall of said casing and a slotted lip portion extending outwardly from one end of the imperforate wall for close-fitting engagement with the walls of said casing, the lip portion of said head upon movement of the latter within the chamber of said casing being engageable with the handle-adjoining end of a mop received within the chamber to crowd the same into engagement with the walls of said casing and the arcuate wall of said head; and means connected with said shaft for imparting limited axial rotation thereto.

4. In a press for wringing water from handle-carried mops; a casing formed with a uniformly arcuate perforate bottom wall and defining an open top chamber for the reception of the yarn body of a handle-carried mop; a rock shaft journaled transversely of said casing; a pressing head connected with and extending radially outwardly from said shaft for swinging movement in an arcuate plane into and out of the chamber of said casing upon rotation of said shaft, said pressing head comprising a uniformly arcuate imperforate wall and a slotted lip extending outwardly from the imperforate wall in following relation thereto for engagement with the handle-adjoining end of a mop positioned in the chamber of said casing, the arcuate wall and lip of said head upon swinging movement of the latter into the chamber of said casing serving to substantially enclose the chamber and to decrease the effective volume thereof, whereby to squeeze a mop contained therein and express water therefrom; and fluid-pressure-actuated means connected with said shaft for imparting limited axial rotation thereto.

5. In a press for wringing water from handle-carried mops; a casing formed with a uniformly arcuate perforate bottom wall and defining an open top chamber for the reception of the yarn body of a handle-carried mop; a rock shaft journaled transversely of said casing; a pressing head connected with and extending radially outwardly from said shaft for swinging movement in an arcuate plane into and out of the chamber of said casing upon rotation of said shaft, said pressing head comprising a uniformly arcuate imperforate wall and a slotted lip extending outwardly from the imperforate wall in following relation thereto for engagement with the handle-adjoining end of a mop positioned in the chamber of said casing, the arcuate wall and lip of said head upon swinging movement of the latter into the chamber of said casing serving to substantially enclose the chamber and to decrease the effective volume thereof, whereby to squeeze a mop contained therein and express water therefrom; and fluid-pressure-actuated means connected with said shaft for imparting limited axial rotation thereto, said last-named means comprising a rocking lever connected with said shaft; a fluid motor having an extensible ram connected with said rocking lever; and foot-oper-

ated pump means for supplying pressure fluid to said motor.
